CARL H. BISSELL AND FRANCIS WARE CLARY, OF SYRACUSE, NEW YORK.

LOOSE-LEAF BINDER.

1,227,740.

Specification of Letters Patent.

Patented May 29, 1917.

Application filed July 16, 1915. Serial No. 40,166.

To all whom it may concern:

Be it known that we, CARL H. BISSELL and FRANCIS WARE CLARY, citizens of the United States, and residents of Syracuse, in the 5 county of Onondaga and State of New York, have invented a certain new and useful Loose-Leaf Binder, of which the following is a specification.

Our invention has for its object the production of a loose leaf binder, which is particularly simple in construction and highly efficient and durable in use; and it consists in the novel features of construction hereinafter set forth and claimed.

15 In describing this invention, reference is had to the accompanying drawings, in which like characters designate corresponding parts in all the views.

Figure 1 is a front elevation of our loose leaf binder, the usual cover being removed 20 and leaves being shown as held by the binder.

Fig. 2 is a section on line A—A, Fig. 1, the covers for the back being also shown.

25 Fig. 3 is a section on line B—B, Fig. 1. Fig. 4 is a horizontal section on line C—C, Fig. 2.

Fig. 5 is a detail view of the upper back section and parts associated therewith.

30 This loose leaf binder comprises, generally, a back, posts carried by the back, a clamping member movable lengthwise of the posts, and means for operating the clamping member. The back is here shown as 35 composed of two telescoping sections, and the posts each include telescoping sections carried respectively by the back sections.

1 and 2 designate the upper and lower sections of the back, each section being shown 40 as formed with end walls 3 or 4, a rear wall 5 or 6, and a top or a bottom wall 7 or 8, the sections being open at their front sides in order that the leaves A may be inserted therein.

45 The sections 1 and 2 telescope with each other and are held from separating in various positions determined by the number of leaves bound therein, by suitable means here shown as latches 9 provided on the end walls 50 of one section and coacting with shoulders 10 provided on the end walls of the other section, the latches having a series of teeth 11 for coacting with the shoulders 10.

55 As here shown, the latches are pivoted at 12 to the inner sides of the end walls 4 of the inner and lower back section 2, and the

shoulders 10 project inwardly from the end walls 3 of the upper outer back section 1 through lengthwise slots 13 in the end walls 4 of the inner section 1. The latches 9 are 60 arranged to move across the slots 13 in position to engage the shoulders 10, and are provided with outturned lips or finger engaging pieces 14, which normally lap the edges of the end walls 3, 4 of the back sections 1, 2. 65

15 and 16 designate the sections of each post, these sections being carried respectively by the top and bottom walls 7, 8 of the back sections, the section 15 being hollow and telescoping within the hollow section 16, and both the sections 15, 16 having alined lengthwise slots, 17, 18. The sections 15, 16 are formed respectively with feet 19, 20 which are secured to the inner faces of the top and bottom walls 7, 8 of the back sec- 75 tions.

21 designates the clamping member movable along each post, this clamping member having a tongue 22 extending through the alined slots 17, 18 into the interiors of the 80 post sections 15, 16, the clamping member having its body extending on the outside of the post in order to press against the leaves A and hold them from separation. As seen in Fig. 4, the clamping member 21 is formed 85 with an arc-shaped passage 23 through which the post extends, this arc-shaped passage forming the tongue 22.

The means for operating each clamping member 21 comprises a screw 24 extending 90 lengthwise of each post in the sections 15, 16 thereof and threading into the tongue 22 of the clamping member, the screw having its head 25 exposed on the outside of the back, as on the upper side of the top wall 7. The 95 screw is held from endwise movement by an annular flange 26 thereon near its head located in the annular recess formed in the foot 19 of the post section 17. The back sections may be provided with suitable cov- 100 ers 27.

In operation, the back sections 1, 2 can be separated by operating the latches 9, this separating movement also separating the post sections and removing the clamping 105 members with the upper post sections 15. The loose leaves are then placed on the lower sections 16 of the posts and the parts again assembled. The clamping members are adjusted to the thickness of the leaves by turning the screw 24. The separation of the backs can be adjusted approximately to the 110

thickness of the leaves by reason of the series of the shoulders 11 of the latches 9.

What we claim is:

1. A loose leaf binder comprising a back, a post carried by the back, a clamping member movable lengthwise of the post, and means for moving the clamping member, said means extending lengthwise of the post and being accessible at one end of the post, substantially as and for the purpose specified. 70
2. A loose leaf binder comprising a back, a hollow post supported by the back, a clamping member movable lengthwise of the post, and means for operating the clamping member, said means extending lengthwise of the post within the same and being exposed at one end of the post, substantially as and for the purpose set forth. 75
3. A loose leaf binder comprising a back, a hollow post supported by the back, a clamping member movable lengthwise of the post, and a screw extending lengthwise of the post and threading into the clamping member and having a head exposed at one end of the post, the screw being held from axial movement, substantially as and for the purpose described. 80
4. A loose leaf binder comprising a back, a post supported by the back, said post being hollow and formed with a lengthwise slot, a clamping member having a tongue extending through the slot and slideable along the interior of the post, and a body on the outside of the post, and means extending lengthwise of the post for operating the clamping member, substantially as and for the purpose specified. 85
5. A loose leaf binder comprising a back, a post supported by the back, said post being hollow and formed with a lengthwise slot, a clamping member having a tongue extending through the slot and slideable along the interior of the post, and a body on the outside of the post, and means extending lengthwise of the post for operating the clamping member, said means comprising a screw threading into the tongue, the screw having a head exposed at one end of the post, substantially as and for the purpose set forth. 90
6. A loose leaf binder comprising a back, a post carried by the back and including telescoping sections, a clamping member movable lengthwise of the sections, and means for operating the clamping member extending lengthwise of the post and having a head accessible at one end of the post, substantially as and for the purpose described. 95
7. A loose leaf binder comprising a back, a post supported by the back and including telescoping sections, said sections being hollow and being formed with alined lengthwise slots, a clamping member having a tongue extending through the slots, and a body on the outside of the post, and means extending lengthwise of the post and coacting with the tongue to operate the clamping member, substantially as and for the purpose specified. 100
8. A loose leaf binder comprising a back, a post supported by the back and including telescoping sections, said sections being hollow and being formed with alined lengthwise slots, a clamping member having a tongue extending through the slots and a body portion surrounding the post, and a screw extending lengthwise of the post and threading into the tongue and having a head exposed at one end of the post, substantially as and for the purpose set forth. 105
9. A loose leaf binder comprising a back, a hollow post formed with a lengthwise slot supported by the back, a clamping member formed with an arc-shape passage through which the post extends, the clamping member having a tongue extending through the slot and into the interior of the post, and a screw extending axially into the post and threading into said tongue, substantially as and for the purpose described. 110
10. A loose leaf binder comprising a back including upper and lower sections, one telescoping within the other, a post supported by the back and including telescoping sections carried respectively by the sections of the back, a clamping member movable lengthwise of the post, and means extending lengthwise of the post and coacting with the clamping member to operate the same, said means having a head exposed on the outside of the back at one end of the post, substantially as and for the purpose set forth. 115
11. A loose leaf binder comprising a back including telescoping sections having lapping end walls, a shoulder projecting from the inner side of the end wall of one section, and a latch pivoted to the contiguous end wall of the other section and lying against the same and coacting with the shoulder on the former end wall, substantially as and for the purpose set forth. 120
12. A loose leaf binder comprising a back including telescoping sections, and a post including telescoping sections carried respectively by the back sections, one of the back sections being formed with a slot in an end wall thereof, and with a pivoted latch movable across the slot and having a series of teeth the latch lying flatwise on said end wall, and the other of the back sections having a shoulder extending through the slot into position to coact with the teeth of the latch, substantially as and for the purpose set forth. 125
13. A loose leaf binder comprising a back including two telescoping sections, a post including telescoping sections carried re- 130

- spectively by the sections of the back, the post sections being hollow and formed with aligned lengthwise slots, a clamping member movable lengthwise of the post and having
- 5 a tongue extending through the slots thereof, means located within the post and extending lengthwise thereof and coacting with the tongue of the clamping member for adjusting the clamping member lengthwise
- 10 of the post said means having a head accessible on the outside of one of the back sections, and means for holding the back sections from separation, substantially as and for the purpose described.
- 15 14. A loose leaf binder comprising a back including two telescoping sections, a post including telescoping sections carried by the sections of the back, the post sections being hollow and formed with aligned lengthwise
- 20 slots, a clamping member movable lengthwise of the post and having a tongue extending through the slots thereof, a screw extending lengthwise of the post and threading into the tongue and having a head exposed on the outside of one of the back sections, the screw being held from endwise movement, and means for holding the back sections from separation, substantially as and for the purpose specified. 25
- In testimony whereof, we have hereunto signed our names in the presence of two attesting witnesses at Syracuse, in the county of Onondaga, and State of New York, this 11th day of February, 1915.
